(57) CLAIM

The ornamental design for a hot button gift card holder, as shown and described.

DESCRIPTION

FIG. 1 is a perspective view of the hot button gift card holder of the present invention.

FIG. 2 is a perspective view of the underside of the hot button gift card holder of FIG. 1.

FIG. 3 is a front view of the hot button gift card holder of FIG. 1.

FIG. 4 is a rear view of the hot button gift card holder of fig. 1.

FIG. 5 is a top down view of the hot button gift card holder of FIG. 1.

FIG. 6 is a bottom up view of the hot button gift card holder of FIG. 1; and,
